GEORG WIENHOLTZ, OF ESSEN-ON-THE-RUHR, GERMANY, ASSIGNOR TO FRIED. KRUPP AKTIENGESELLSCHAFT, OF ESSEN-ON-THE-RUHR, GERMANY.

WHEELED GUN-CARRIAGE.

1,079,816.

Specification of Letters Patent. Patented Nov. 25, 1913.

Application filed February 13, 1913. Serial No. 748,183.

To all whom it may concern:

Be it known that I, GEORG WIENHOLTZ, residing at Essen-on-the-Ruhr, Germany, a subject of the Emperor of Germany, have 5 invented a certain new and useful Improvement in Wheeled Gun-Carriages, of which the following is a specification.

This invention relates to that class of wheeled gun carriages which have a reversible cranked axle-tree, in order that their 10 height of fire may be altered. According to the present invention gun carriages of this kind are provided with an arrangement which reduces the expenditure of power 15 necessary for moving the gun carriage from small to great firing heights.

In the drawing Figure 1 shows a side elevation of a constructional example of the 20 subject matter of the invention with one of the front wheels of the gun carriage broken away, Fig. 2 is the corresponding plan view, partially in section on the line 2-2 of Fig. 1. Fig. 3 is a portion of Fig. 2 drawn to a larger scale and, Fig. 4 is a 25 section on the line 4-4 of Fig. 1 drawn to the same scale as Fig. 3.

The axle, for the gun carriage wheels G, is cranked and consists of the cranked outer portions A and the middle portion 30 A¹, which is carried by and rotates in the body B of the gun carriage. The axle-tree is secured in different 35 positions by bolts or the like, which are not shown in the drawing, and by means of which the cranked arms a² of the outer portions A of the axle-tree can be coupled to the body of the gun carriage.

The middle portion A¹ of the axle-tree is 40 provided for nearly the whole of its length with an axial boring a³. This boring serves for the reception of a spring accumulator, which consists of a helical spring C and a bolt D. The spring C is coiled around the bolt D and its end c¹, engages a collar d² 45 (see Fig. 3) on the bolt D and its other end c² engages a recess a⁴ (see Fig. 3) in the portion A¹ of the axle-tree. The bolt D is centered in the boring a³ by a pin d³ (see Fig. 3) on the bolt, which enters a boring 50 a⁵ in the axle-tree and by a sleeve E, which is mounted on the axle-tree and closes the boring a³. The bolt D is prevented from moving in an axial direction by the collars d¹, d² (see Fig. 3), the collar d² bearing 55 against the inner end of the boring a³, while

the collar d¹ bears against the sleeve E. The end d⁴ of the bolt D, projecting from the sleeve E, is connected by a feather and groove with an arm F so as to be incapable of rotating, and the said arm F is rigidly 60 secured, as shown in Figs. 1 and 4, to one of the covers b¹ of the bearings for the portion A¹ of the axle-tree. In consequence of this arrangement the bolt D is prevented from rotating relatively to the body B of 65 the gun carriage.

When the axle-tree is in the position as shown in full lines in Fig. 1, which position corresponds to the lowest firing height of the gun carriage, the spring C possesses 70 a certain amount of stress. The direction in which the spring C is coiled is so chosen, that it uncoils when the portion A¹ of the axle-tree rotates in the direction of the arrow x (see Fig. 1) relatively to the body of 75 the gun carriage.

When the gun carriage is to have a greater firing height given to it, than that shown in the drawing, the axle-tree is rotated relatively to the wheels, in such a manner that 80 the cranked arms a², of the outer portions A of the axle-tree, are rocked in the direction of the arrow y (see Fig. 1). When this takes place, the middle portion A¹ of the axle-tree is rotated relatively to the body B 85 of the gun carriage in the direction of the arrow x, so that the spring C uncoils and consequently facilitates the shifting of the gun carriage into the greater firing height, shown by dot and dash lines in Fig. 1. 90 When the gun carriage is let down again to a lower firing height the spring C is again stressed.

I claim:

1. In a wheeled gun carriage having a 95 trail, a cranked axle-tree, bearings in said trail in which the middle cranked portion of the axle-tree is mounted to oscillate, a spring accumulator one end of which is secured to the trail and the other end to the axle-tree in such a manner that the spring is compressed when the trail is in the lowest position and partly or wholly released when the trail is in the highest position. 100

2. In a wheeled gun carriage having a 105 trail, a cranked axle-tree, bearings in said trail in which the middle cranked portion of the axle-tree is mounted to oscillate for the purpose of giving different heights to 110

- said trail; the middle portion of the axle-tree being hollow, an accumulator in the hollow portion of the axle-tree, said accumulator comprising a helical spring, a 5 spindle for said spring, one end of the spring being secured to said spindle and the other end thereof to said middle portion of the axle-tree; and means for rigidly connecting said spindle to the trail.
- 10 3. In a wheeled gun carriage having a trail, a cranked axle-tree, bearings in said trail in which the middle cranked portion of the axle-tree is mounted to oscillate for the purpose of giving different heights to 15 said trail; the middle portion of the axle-tree being hollow, an accumulator in the

hollow portion of the axle-tree, said accumulator comprising a helical spring, a spindle for said spring, one end of the spring being secured to said spindle and the other end 20 thereof to said middle portion of the axle-tree; an arm keyed to said spindle and rigidly secured to the trail; said accumulator having its greatest stress when the trail is in the lowest position.

25

The foregoing specification signed at Bar-
men, Germany, this 27th day January, 1913.

GEORG WIENHOLTZ. [L. s.]
